(57) **CLAIM**

The ornamental design for a painter's bucket, as shown and described.

DESCRIPTION

FIG. 1 is a perspective view of a painter's bucket showing my new design;

FIG. 2 is a bottom plan view thereof;

FIG. 3 is a side elevation view thereof, the opposite side elevation view being a substantial mirror image thereof;

FIG. 4 is a top plan view thereof; and,

FIG. 5 is a front elevation view thereof.
